GAME AND GAME-BOARD APPARATUS

James R. Thomas, Oklahoma City, Okla., assignor of one-eighth to Fannie Wilder Thomas, one-eighth to Muriel Thomas Matthews, one-eighth to Ruth Thomas Koock, one-eighth to Helen Rebecca Thomas, all of Oklahoma City, Okla., one-eighth to Roswell W. Thomas, Birmingham, Mich., one-eighth to James Gladwyn Thomas, Champaign, Ill., one-eighth to H. Emerson Thomas, Forest Hills, N. Y., and one-eighth to Harry R. Thomas, Bartlesville, Okla.

Application August 23, 1938, Serial No. 226,272

5 Claims. (Cl. 273—134)

This invention relates to a game and to a game-board apparatus adapted thereto. It relates more particularly to a game of entertainment and instruction which can be played for amusement.

5 While this game is educational and may be played by one person alone, it will generally be played for amusement by a plurality of persons at any one time, and may be most conveniently played by any number of players between two and 10 eight inclusive. It is an educational game in that it is designed to instruct the players in the prospecting, producing, and marketing phases of the oil industry. However, there are certain features 15 of my game which I believe to be novel and new as regards games in general, and insofar as these novel features are concerned, I do not desire to be restricted to a game which deals only with the oil industry.

It is an object of my invention to provide a 20 game in which the play is carried out in at least two distinct phases.

It is a further object of my invention to provide a game comprised of at least two phases, the first of which represents an attempt to reach 25 a desirable goal, and the second of which represents a series of events which result from the attainment of a goal.

Still another object of my invention is to provide a game representing the oil industry.

30 A further object of my invention is to provide a game in which is represented first, the prospecting for oil or the drilling of an oil well, and second, the production of oil and/or marketing in connection therewith.

35 Other objects and advantages will become apparent as the following disclosure and discussion proceed.

Various features of my invention will now be described in connection with various features of 40 the oil or petroleum industry in general. Many people living in all parts of the United States, and foreign countries, are acquainted with few, if any, of the actual and interesting drilling, producing, storing, and marketing operations of the 45 petroleum industry, although many of these same people may be familiar with the motor-fuel service stations which are a common sight in most communities. In playing my game, as adapted to the petroleum industry, it is possible to carry 50 on realistic operations of an oil business, and the players are thus educated as well as entertained.

The playing board of my game may be constructed of cardboard, heavy paper, wood-board, or metal sheeting, or the like, of any convenient 55 dimensions. A convenient and preferred board

can be made by drawing a suitable design, to be hereinafter more fully described, on heavy paper which is preferably in the shape of a square, although it can have any other more or less regular polygonal figure. The playing board has two 5 separate paths or courses, preferably one inside the other, running around the outside edges, parallel thereto and to each other, one of which is a "drilling" path or column, and the other a "producing" and/or "marketing" path. A player progresses along one or the other of these paths in a series of moves, and each of these paths is divided into a convenient number of spaces, a player in any particular move passing over a certain number of spaces and ending his move upon one 10 of them. Some of these spaces are designated with various penalties or rewards, so that when a player's move ends upon such a space, he gains 15 or loses in the play in whatever manner is designated on the space. These spaces, on the 20 "drilling" path or column, indicate various conditions which might be met in drilling for oil, while in the "producing" path or column, they indicate various conditions which might be met in the producing and/or marketing of oil, as will be 25 more specifically described hereinafter. The "drilling" column terminates in a series of spaces which represent the actual completion of an oil well, each of these spaces representing an oil 30 well of various capacities, including zero capacity, or in other words, a "dry hole".

The length of a player's move is equal, in 35 spaces, to a number which is determined by chance, as by a throw of a die or of dice, or the operation of some other chance-determining element. The actual movements and positions of the players are conveniently represented by the 40 movements and positions of various tokens, one for each player. These tokens can be of various sizes and designs—such as miniature trucks, tank cars, engines, tools, oil tanks, or other convenient equipment related to or used in the petroleum industry, or any other convenient articles or shapes. A supply of miniature oil storage tanks, or the like, is provided for the use of the players 45 in accounting for oil they own in storage, acquired by production, or by purchase. A supply of miniature oil-well derricks, or some other convenient set of articles such as pins, is provided for 50 the use of the players in accounting for oil wells completed, either as producers or as dry holes. A supply of imitation or play money or the like is provided for use in making transactions in the 55 payment of drilling, oil storage, and other ex-

penses incident to prospecting for, producing, and marketing of oil, and the like.

The actual apparatus or implements employed in playing one modification of my invention will now be described in connection with the drawing which forms a part of this specification.

Fig. 1 represents diagrammatically approximately one-half of a board suitable for playing such a game, the half not shown being essentially a duplicate of the half shown.

Fig. 2 represents diagrammatically certain tokens and other implements, not drawn to scale, which may be used by the players in playing the game.

In Fig. 1, 20 represents the playing board in general, which serves as a playing field and which, in this case, is in the shape of a square. Around the periphery of this board, and parallel to the sides thereof, are two courses or tracks, one of which, 21, is designated as a "Drilling column" and the other, 22, is designated as a "Producing and marketing column". Each of these courses is divided into a series of spaces. In this instance the inner course 21 is divided into a total of forty-eight spaces, of which there are twelve along each side, which may be numbered serially, and the outer course 22 is divided into a total of seventy-two spaces, of which there are eighteen along each side, which may be numbered serially also. These numerals, however, have not been shown. In neither case are these numerals significant as to the space, other than to number them serially, and in that manner aid in the play. By turning the half of the board shown through an angle of 180° about the center of the line which divides the total board into two halves, and in the plane of the board, the unshown half of the board for this modification can be determined.

In each of the courses some of the spaces are labeled to indicate various conditions or situations encountered. In the case of the course 21 these conditions or situations are similar to those which a driller might encounter in drilling an oil well, some of which are favorable to his progress, such as "Shale formation, easy drilling", "Sand formation, easy drilling", and the like, and some of which are unfavorable to his progress, such as "Lime formation, hard drilling", "Set casing, pay supply company", "Delay, drillers gone to town", and the like. It will readily be seen from the frequency and titles of the unfavorable situations that the game truly reflects the conditions of the actual drilling of a well, wherein numerous and extensive adverse conditions are often encountered. In the case of the course 22 these conditions and situations are similar to those encountered in the production and marketing of petroleum, some of which are favorable to a person so engaged, such as "Sell oil on hand to refinery", "Oil flow from wells to tank", "Get bids for oil", and the like, while some of these conditions are unfavorable, such as "Well gone dry—abandon", "Storm—lightning strikes tanks", and the like. In this modification, the conditions and situations pertinent to crude oil only have been shown. It will, of course, be understood that the refining of oil and/or the marketing of refined products may be represented, in addition to or in the place of the production and marketing of crude oil.

It is not necessary that all of the said spaces in either one or the other course be designated to represent conditions encountered in the field of endeavor concerned, nor is it necessary that such spaces be arranged or distributed in any

particular order or grouping. Spaces not so designated may be left blank, or may be colored as desired, or may contain pictures or scenes pertinent to or reminiscent of the petroleum industry.

Extending from each of the four corners toward the center of the board are diagonal paths 23 which also comprise a series of spaces, a series of six spaces being indicated in the present modification which may be numbered serially toward the center of the board. In the present instance, all these spaces are indicated as being blank spaces. It is intended that these paths should be continuations of the "Drilling column" or course 21, and they lead directly to a series of spaces which represent a completed well. However, if it is so desired, any or all of these spaces may be designated to indicate conditions favorable or unfavorable to a player, as discussed in connection with course 21. If such is done, all of the said paths 23 should be the same length and have similar indications at similar points along their length. The oil derricks 24 are, in this modification, used only for decoration. If desired the paths 23 may extend throughout part or all of the length of the derricks 24.

The paths 23 terminate in a series of spaces 25 to 30, inclusive, which represent a completed oil well. These spaces represent various initial capacities of a completed oil well, including a "dry hole", or no production at all, as indicated by the space 30.

In a part of the area of the playing board 20 there are provided various portions or sub-areas which may be of help to indicate and record quantities of petroleum acquired by production or purchase, producing oil wells, dry holes, and the like. The oil is preferably stored in tank farms 31, one for each player. In each tank farm there are indicated sites for tanks having various capacities upon which can be placed various tokens to indicate stored oil such as the tokens or tanks 32 to be hereinafter described. There are also various leases 33, on which may be placed indicia, such as tokens or oil well derricks 34 to be hereinafter described, each time a player completes a circuit of the course 21 and travels down a given path 23 to complete a well by attaining one of the spaces 25—30.

Referring now more particularly to Fig. 2, a symbol or token is generally provided for each player which represents the player and by means of which his position during play may be indicated and followed. I have herein represented eight such tokens at 40 to 47, inclusive, which are respectively an engine 40, a tank truck 41, a tank car 42, an oil drum 43, an oil can 44, a wrench 45, a gasoline pump 46, and an automobile 47. Other distinctive tokens or symbols may, of course, be provided if and as desired. It is preferable that such tokens represent in miniature diversified objects which are pertinent to the subject in connection with which the game is being played, inasmuch as this adds more interest to the game. In addition there is provided any suitable chance-determining element or means, such as the two dice 50, which are of common knowledge. A number of miniature oil well derricks, such as oil well derrick 51, are provided, by means of which the number of wells drilled by a player may be indicated. Such miniature wells may be provided with a pin or pin-like extension on the bottom, as indicated in the drawing, so that they may be somewhat rigidly fixed in suitable holes in the lease areas 32. Miniature tanks 52 may be provided to indicate and aid in recording oil in stor-

age. Preferably they will have the same cross-sectional area as the tank sites in the tank farms 31, and may have their capacities indicated, as shown. If desired, all tanks of one capacity may also have the same color, which will be different from the color of tanks having other capacities. Play money of various denominations, which is not specifically shown but which is commonly used in many games, may be provided in substantial quantities. A suitable frame work or "lightning rod" 53 may be provided which can be acquired by a player if and as he may desire, and for a price, to protect certain storage tanks from the full penalty of being struck by lightning, as can be provided for in the rules for playing the game.

One specific embodiment of my invention will now be further described in connection with certain rules by which such a game may be played. 20 These rules have been found to be satisfactory for playing my game and providing considerable amusement and instruction in the playing thereof. However, it is to be understood that such rules may be changed at various places without changing materially the character of the game or without changing the fundamental principles upon which my game is based.

Each player is given or assigned \$50,000 (or some other convenient amount) of play money 30 or capital, and a token for use in moving around the playing board. A convenient distribution of \$50,000 capital initially given each player when such is distributed in play money is: seven 5-thousand dollar bills, ten 1-thousand dollar bills, eight 5-hundred dollar bills, and ten 1-hundred dollar bills, in the imitation or play money provided. However, instead of using such play money, the game may be satisfactorily, and sometimes more easily played if simple accounts are kept for each player upon a score pad or other piece of paper. A pair of dice, which is used by all players, is also provided.

Some person, who may be one of the players, is chosen as treasurer to administer the refinery, supply house and drilling contractor funds, and to issue oil-well derricks and oil storage tanks as they are required, and to receive and disburse the play money and/or keep accounts.

Each player throws the dice and the player throwing the highest number begins the play, the player to the left of first player is second, and so on around in turn. Each player is allotted a corner of the board (if there are more players than corners, two players may start from each of one or more corners) from which his play begins. Each player throws the dice in turn and proceeds with the play, moving his token in the drilling column 21 the number of spaces indicated upon the throw of the dice. Penalties and rewards are received by the players as indicated in the spaces upon which the token stops at the end of each turn, if such is indicated. After a player has gone around the complete circuit of the drilling column 21, and his token has been 60 returned to its starting place, the play continues on the corresponding diagonal track 23 into the center of the board in order to complete the drilling of the well. In order to finish the oil well, either as a producer or a dry hole, the total 65 number of the dice must be used in the final move in completing the well. If this number is too large, the player must wait until his turn comes again, before he may throw the dice again and attempt to complete his well. With the arrangement shown, a modification of this rule 70

may be that the number used in the final move may be the total number of the dice, if this is six or less, or the larger number indicated by one die is used if the sum is over six.

If a well is completed as a dry hole, it is necessary to return to the drilling column to drill another well; this procedure is repeated until a producing oil well is completed. After completing a producing oil well, the player begins at his designated starting corner in the outermost column 10 or producing and marketing column 22, moving his token the indicated number of spaces upon the throw of the dice and receiving the benefits or penalties as required from the spaces upon which the token stops at the end of each turn. 15

After completing the circuit of the producing and marketing column, the player begins the drilling of another well by starting his token again in the drilling column 21. In going from the producing and marketing column to the drilling column, the player may use the remaining number of moves allowed by the throw of the dice, it not being necessary to throw the dice so that the token stops on the last space in the producing and marketing column before going back 25 into the drilling column. After another oil-producing well has been completed, the player then again returns to producing and marketing column. This alternate playing in the drilling column and producing and marketing column is 30 continued until a determined number of wells has been drilled and completed, at which time the player continues to move his token around the producing and marketing column until the game is terminated or until he goes "broke" and 35 is eliminated from the game. After a player has completed a producing oil well and has oil stored in his tanks on his tank farm, he may buy and sell oil from other players who have oil in storage or desire to purchase oil. 40

As the playing progresses, the players are required to pay out money in penalties as well as to receive money in rewards when their tokens stop on spaces so designated. In this manner the players either reduce or increase their original 45 \$50,000 cash capital, or cash assets if an accounting system is used. Any amount of cash may be decided upon as the winning figure; doubling the original \$50,000 cash has been found to be a convenient figure. In other words, the 50 first player who obtains \$100,000 in cash is declared winner and the play is terminated.

Any number of oil wells may be drilled. The playing time is determined by the number of players and the number of wells it is decided to 55 drill. The completion of four producing wells by each player has been found satisfactory. A player may "go broke" by paying out all of his capital in penalties or in other ways, so that all of his money and resources are exhausted. In 60 such a case the player is eliminated from the game.

There are spaces in the producing and marketing column which are designated "Well gone dry—abandon and return to drilling column". 65 When a player ends his move upon one of these spaces, it is generally understood that he is to abandon only one producing oil well, although of course he loses by this none of the oil already produced from the well which must be abandoned.

Although my invention has been described particularly in connection with the production and marketing of oil, it is not necessarily always to be restricted to this modification. Other com- 75

mercial enterprises which are divided into two or more phases may also be represented by somewhat similar modifications. As only one example, the building of an apartment house or hotel might well be a first phase, with renting of the apartments or rooms a second phase.

What I claim is:

1. A board game apparatus, including, in combination, a board having a series of spaces constituting a path affording a first continuous track for the continuity of play, certain of said spaces being designated to inflict penalties upon a player who ends a move thereon and others of said spaces being designated to provide benefits to a player who ends a move thereon, the said first track terminating in one of a series of goals each favorable to a player in a degree different from the others, a second series of spaces affording a second continuous track for the continuity of play, certain of said spaces being designated to inflict penalties upon a player who ends a move thereon, and other of said spaces being designated to provide benefits to a player who ends a move thereon.
2. In a game board apparatus, the combination comprising a board constituting a playing-field, a first circumferential path around said field representing the drilling of an oil well and comprising a series of spaces representing various conditions encountered in the drilling of an oil well, a diagonal path comprising a series of spaces and leading from the termination of said first path toward the center of said board and terminating in a series of zones each representing a producing oil well of a capacity different from the others, a second circumferential path around said field representing various conditions encountered in the marketing of oil, said first path and diagonal path to be traveled by a player before said second path is traveled.
3. A game apparatus adapted to be played by

a plurality of players each having a movable playing piece and each operating in turn means for indicating the number of increments said piece is to be moved along a playing path, which comprises a playing board having a first marked path of travel comprising a plurality of distinct increments and having at one end a series of goals of different values, only one of which goals is to be attained by any one player at the end of any one trip along said first path, and at least one other marked path of travel comprising a plurality of distinct increments, said second path to be traveled by each player only after said first path has been traveled and one of said goals attained.

4. A board game apparatus adapted to be played by a plurality of players, which comprises a board constituting a playing field, a first path on said board comprising a series of spaces which constitute a continuous track for continuity of play for each player, a series of goals of different values, said first path ending with one of said series of goals of different values at least one of which is adapted to return the player to the start of said path, a second and independent path on said board comprising a series of spaces which constitute a continuous track for continuity of play, said second path to be traveled by each player, after attaining a goal which does not return him to said first path.

5. A board game apparatus including in combination, a board constituting a playing-field and having a series of spaces constituting a path affording a first continuous track for the continuity of play, the said first track terminating in one of a series of goals each favorable to a player in a degree different from the others, and a second series of spaces affording a second continuous track for the continuity of play.

JAMES R. THOMAS. 40
